UNITED STATES PATENT OFFICE.

JAMES C. LOUCKS, OF GRAND RAPIDS, MICHIGAN, ASSIGNOR OF ONE-HALF
TO THOMAS F. DONAHUE, OF GRAND RAPIDS, MICHIGAN.

FOOT-VALVE.

SPECIFICATION forming part of Letters Patent No. 743,006, dated November 3, 1903.

Application filed June 29, 1903. Serial No. 163,523. (No model.)

To all whom it may concern:

Be it known that I, JAMES C. LOUCKS, a citizen of the United States, residing at Grand Rapids, in the county of Kent and State of Michigan, have invented certain new and useful Improvements in Foot-Valves; and I do hereby declare the following to be a full, clear, and exact description of the invention, such as will enable others skilled in the art to which it appertains to make and use the same.

My invention relates to improvements in foot-valves, and its object is to provide means for readily clearing the strainer from any obstructions that may have accumulated thereon; and it consists in the combination and arrangement, with the valve, of a supplementary valve opening oppositely to the check-valve of the device and provided with a yielding support to retain this supplementary valve in closed position under ordinary pressures and to yield and permit the valve to open and the fluid retained by the foot-valve to flow backward and through the strainer, and thus clear the strainer from any obstructions that may have accumulated thereon, as will more fully appear by reference to the accompanying drawings, in which—

Figure 1 is a vertical section of a device embodying my invention; Fig. 2, a side elevation of the same with the parts broken away to show the construction and showing the operation when acting to clear the strainer, and Fig. 3 a plan view of the supplementary valve-seat.

Like letters refer to like parts in all of the figures.

A represents the packing of the main valve, and B the plate of the same. These are made annular, and thus provided with a suitable 40 central opening, which opening is closed by an auxiliary valve D, provided with packing G. This auxiliary valve is supported by a suitable valve-seat of the form indicated in

Fig. 3, and on the stem of the valve D, which 45 passes through the cross-bar of this valve-seat, is a suitable head E, and a spring F is interposed between this head and the cross-bar of the valve-seat, whereby the valve D is supported in contact with the seat under

the ordinary back pressure upon the valve A. 50 As long as this pressure is not in excess, the valve D remains closed, and the valve A operates in the usual manner.

H represents the valve-casing, of the usual construction and provided below the valve 55 with the usual screen I. Whenever this screen becomes clogged for any reason, any suitable means of increasing the back pressure on the valve A will at once open the valve D, and the fluid above the valves will then flow back- 60 ward, as indicated by the arrows in Fig. 2, and thus its reverse movement through the strainer will clear the same of any obstructions that may have accumulated thereon.

It is obvious that various modifications of 65 structure may be adopted without departing from my invention. I therefore do not limit myself to the precise construction shown.

Having thus fully described my invention, what I claim, and desire to secure by Letters 70 Patent, is—

1. In a foot-valve, in combination with the case, a strainer, and a valve; an auxiliary valve opening toward the strainer, and a spring to hold the said valve closed against 75 the pressure on the first-named valve.

2. In a foot-valve, the combination of a case, a strainer, an annular valve opening away from the strainer, a valve opening toward the strainer, and closing the opening in 80 the first-named valve, and a spring to hold the second-named valve closed.

3. In a foot-valve, the combination of a case, a strainer, an annular valve opening away from the strainer, a valve-seat on the 85 under side of said valve and having a cross-bar, an auxiliary valve engaging the valve-seat, and having an upwardly-projecting stem provided with a head, a spring surrounding the stem and engaging the head, and the 90 cross-bar of the valve-seat to hold the valve closed.

In testimony whereof I affix my signature in presence of two witnesses.

JAMES C. LOUCKS.
